Primary Examiner — Derrick Holland(74) *Attorney, Agent, or Firm* — Snell & Wilmer LLP(57) **CLAIM**

The ornamental design for a thermocouple, as shown and described.

DESCRIPTION

FIG. 1 is a perspective view of a thermocouple;

FIG. 2 is a side view thereof; and,

FIG. 3 is a top view thereof.

The broken lines shown represent unclaimed subject matter and form no part of the claimed design.

1 Claim, 2 Drawing Sheets# US D702,188 S
